US0D1047423S

(12) **United States Design Patent** (10) **Patent No.:** **US D1,047,423 S**
(45) **Date of Patent:** **** Oct. 22, 2024**

(54) **HANDGUN HOLSTER**

(71) Applicant: **Jonathan Hauptman**, Maplewood, MN (US)

(72) Inventor: **Jonathan Hauptman**, Maplewood, MN (US)

(73) Assignee: **PHLster LLC**, Hugo, MN (US)

(**) Term: **15 Years**

(21) Appl. No.: **29/851,703**

(22) Filed: **Aug. 31, 2022**

(51) **LOC (14) Cl.** **03-01**

(52) **U.S. Cl.**

USPC **D3/222**

(57) **CLAIM**

The ornamental design for a handgun holster, as shown and described.

DESCRIPTION

FIG. 1 is an isometric view of a handgun holster showing my new design;

FIG. 2 is another isometric view of the handgun holster shown in FIG. 1;

FIG. 3 is a front elevational view of the handgun holster shown in FIG. 1;

FIG. 4 is a right side elevational view of the handgun holster shown in FIG. 1;

FIG. 5 is a rear elevational view of the handgun holster shown in FIG. 1;

FIG. 6 is a left side elevational view of the handgun holster shown in FIG. 1;

FIG. 7 is a top plan view of the handgun holster shown in FIG. 1;

FIG. 8 is a bottom plan view of the handgun holster shown in FIG. 1; and,

FIG. 9 is an isometric view of the handgun holster shown with additional hardware that forms no part of the claimed design.

The broken lines shown in the Figures are included for the purpose of illustrating environment and portions of the handgun holster that form no part of the claimed design.

1 Claim, 8 Drawing Sheets
